UNITED STATES PATENT OFFICE.

JOSEPH A. GROEBLI, OF NEW YORK, N. Y.

BEAD-SEWING MACHINE.

Application filed July 16, 1923. Serial No. 651,768.

To all whom it may concern:

Be it known that I, JOSEPH A. GROEBLI, a citizen of the United States, and a resident of the city, county, and State of New York, have invented certain new and useful Improvements in Bead-Sewing Machines, of which the following is a specification.

My invention relates to an improvement in the means for feeding beads in bead sewing machines, after they have passed the bead separator and while they are traveling down to the fabric, and to supporting the bead thread against distortion during the formation of the stitch; and my improvements are directed particularly to the employment of positively acting mechanical means which will follow the bead down and, if it lags, push it down to or close to the fabric, and will, also, act as a guide or support to the bead thread and to the stitching thread in the process of forming the stitch, so that the bead will be positively brought to the proper position, and the threads will assume their correct relations for holding it in place with precision and accuracy.

An embodiment of my invention, in means suitable for carrying it into operation, is shown in the accompanying drawings, in which Fig. 1 is a side elevation, with some parts in section, of the head of a sewing machine with my improved mechanism mounted thereupon; Fig. 2 is a similar view taken as looking to the left on Fig. 1; Fig. 3 is a cross sectional view taken as looking down on line 3—3 of Fig. 1; Figs. 4, 6, 8, 10, 12, and 14 are a series of views illustrating in elevation the successive positions of the mechanisms during a stitch cycle; and Figs. 5, 7, 9, 11, 13 and 15 illustrate in plan the same successive positions of the mechanism, exclusive of the bead separator; Figs. 16, 17 and 18 are details.

Similar reference numerals designate the same parts in all the figures.

My improvements are applicable to machines of the general type illustrated in my Letters Patent Number 1,445,764 of February 20th, 1923; and the method of their embodiment in such machines may be readily understood by referring to my aforesaid patent for an illustration of the requisite

operative parts of the mechanism which are not shown in the drawings forming part hereof.

A bead separator 1, the novel features of which are the subject of a separate application Serial No. 651,769, filed July 16, 1923, and, for that reason, are not herein described in fuller detail, is carried by a tube 53, which corresponds to the tube 53 of my aforesaid patent; and the tubes 38 and 95 correspond to the tubes similarly numbered in the same patent.

On the driving shaft 33, is mounted a cam 2, which travels against the upper end of a bar 4, slidably mounted in the head 5 of the machine, and pressed against the cam by a spring 6 interposed between it and the head, the upper end of the bar being provided with a suitable track 7 for the cam to rotate against.

To the lower end of the bar 4 is attached an arm 8 having a ring end 9 surrounding the lower portion of the machine head, so as to leave an open space between it and the ring 9.

The collar 10, which is attached to the end of the tube 95, and carries the presser foot 11, is provided with a pin 12, the ends of which pass through sockets in flanges 13, 14 on a bar 15, so that the bar may slide up and down on the pin.

The upper end of the bar 15 is provided with a slot 16 which adapts it to straddle the ring 9, but loosely enough to permit it to be turned to and fro through the slot.

An arm 19 is journalled on the pin 12, and is fitted with a rabbet 20 in which the bar 15 slides; so that if the arm 19 is swung to and fro it will rock the bar 15 around the pin 12.

A spring 21, stretched between the collar 10 and the bar 15, keeps the end of the arm 19 pressed against the face of a cam 23 which is carried by the tube 38. Consequently when the tube revolves, the arm 19 will be swung to and fro by the cam 23.

The bar 15 carries an arm 25, terminating in an inwardly turned, forked end 26 disposed below the bead separator, which is illustrated as being of the gripping type, wherein a pivoted jaw 27 is opened and closed through an arm 28 being rocked by a

cam collar 29 carried by the tube 38, an arm 30 reciprocating below the jaw, to hold up the beads when the jaw is open and to drop one bead when the jaw is closed; this dropping of the bead taking place once for each revolution of the tube 38. This bead separating mechanism is the subject of a separate application.

The tube 38 also carries with it the thread guide 31, which supplies the stitching thread 32 to the needle 34, in the well known manner, casting the thread around both the needle 34 and the bead thread 35, in the process of forming the stitch.

15 The operation of the machine is as follows:—

Assuming that the parts are in a position where a bead 40 has been released by the arm 30 and has started to slide down the thread 35, and the forked end 26 of the arm 25 has been swung around so as to straddle the thread 35, the adjustment of the mechanism is such that the rotation of the cam 2, will depress the bar 4 and its arm 8 and the ring 9, sliding the bar 15 down on the pin 12 so that the forked end 26 of the arm 25, will follow the bead down along the thread, as illustrated in Figs. 4 to 13 inclusive, and will push the bead before it if the bead shows any tendency to hang on the thread or not to drop promptly down to the fabric, in which case there would be danger of the stitching thread being fouled by passing around the bead thread below the bead a second time.

35 During this movement of the bead follower arm 25, the needle 34, which was partially raised, has been elevated to its highest point and then lowered until, when the guide 31 is on the side of the needle opposite to its 40 barb, the barb of the needle will catch the thread and draw it through the loop previously formed around the needle's shank; the movement of the thread guide being timed to swing its thread over the end 26 of the arm 25, and above it and the bead 40, thereby preventing the stitching thread from passing under the bead a second time and being fouled, and to continue around the thread 35, which will be laterally supported, 45 against the lateral drag of the stitching thread, by the fork of the end 26 until the turn around it has been partially completed. During the latter part of this movement the bead separator jaw has opened and allowed 50 another bead 41 to drop down on the arm 30, by which it is released, as shown in Figs. 12 and 13, and allowed to start down the threaded 35.

60 The shoulder of the cam 23, however, rocks out the arm 19, swinging the bar 15 and its arm 25 around so as to draw the forked end of 26 out of the path of the bead 41, while at the same time the bar 15 and its arm 25 are raised by the sliding upward of the bar 4, under the influence of the spring

6, as the short axis of the cam 2 is brought over the bar 4.

The continued travel of the cam allows the arm 19 to rock back, so that the forked end of arm 26 is swung forward to again straddle 70 the thread 35, as in Figs. 4 and 5.

The cycle of movements is then repeated for the next stitch.

In this way each bead, after having been released by the separator or dropper, is followed down by the follower until it reaches its proper position for attachment to the fabric; the bead thread is supported against lateral displacement; and the stitching thread is prevented from fouling under the 80 bead; so that a high degree of accuracy is assured in the operation of the machine, and defective work, because of delayed movement of the beads or defective cooperation of the threads, is very effectually guarded against. 85

It will be understood that the mechanism shown is used as an illustrative type of a suitable embodiment of my invention, and not as an exclusive form thereof. For details of construction might be modified, as 90 by the use of mechanical equivalents or the like, without departing from the scope of my invention as claimed.

Having thus described my invention, what I claim and desire to secure by Letters 95 Patent of the United States, is:—

1. In a bead sewing machine embodying means for supplying a thread carrying loosely strung beads, bead separating means, and means for winding a stitching thread 100 around the bead thread between every two stitches, the combination of movable, mechanical means engaging with the beads and propelling them forward beyond their point of final separation. 105

2. In a bead sewing machine embodying means for supplying a thread carrying loosely strung beads, bead separating means, and means for winding a stitching thread around the bead thread between every two 110 stitches, the combination of movable, mechanical means engaging with the beads successively and propelling them forward one by one beyond their point of final separation, and common means for actuating the separating means and the propelling means in synchronism. 115

3. In a bead sewing machine embodying means for supplying a thread carrying loosely strung beads, bead separating means, and means for winding a stitching thread around the bead thread between every two stitches, the combination of movable, mechanical means engaging with the beads and propelling them forward beyond their point of final separation the range of movement of said mechanical means permitting it to follow the beads to their selected positions on the fabric. 120

4. In a bead sewing machine embodying 125

means for supplying a thread carrying loosely strung beads, bead separating means, and means for winding a stitching thread around the bead thread between every two 5 stitches, the combination of vertically movable mechanical means adapted to propel the beads forward beyond their point of final separation.

5. In a bead sewing machine embodying 10 means for supplying a thread carrying loosely strung beads, bead separating means, and means for winding a stitching thread around the bead thread between every two 15 stitches, the combination of means, radially movable relative to the bead thread, adapted to propel the beads forward beyond their point of final separation.

6. In a bead sewing machine embodying 20 means for supplying a thread carrying loosely strung beads, bead separating means, and means for winding a stitching thread around the bead thread between every two 25 stitches, the combination of means, vertically and radially movable relative to the bead thread, adapted to propel the beads forward beyond their point of final separation.

7. In a bead sewing machine embodying 30 means for supplying a thread carrying loosely strung beads, bead separating means, and means for winding a stitching thread around the bead thread between every two 35 stitches, the combination of projectable and retractable means adapted to propel the beads forward beyond their point of final separation.

8. In a bead sewing machine embodying 40 means for supplying a thread carrying loosely strung beads, bead separating means, and means for winding a stitching thread around the bead thread between every two 45 stitches, the combination of movable means, moving between the bead separator and the fabric, intermittently engaging with the bead thread and forming a lateral support for it against a lateral drag of the stitching thread.

9. In a bead sewing machine embodying 50 means for supplying a thread carrying loosely strung beads, bead separating means, and means for winding a stitching thread around the bead thread between every two 55 stitches, the combination of movable means, moving between the bead separator and the fabric, intermittently slidably engaging with the bead thread and forming a lateral support for it against a lateral drag of the stitching thread.

10. In a bead sewing machine embodying 60 means for supplying a thread carrying loosely strung beads, bead separating means, and means for winding a stitching thread around the bead thread between every two 65 stitches, the combination of movable means, moving between the bead separator and the fabric, intermittently engaging with the

bead thread between the bead and the stitching thread and forming a lateral support for the bead thread against a lateral drag of the stitching thread.

11. In a bead sewing machine embodying 70 means for supplying a thread carrying loosely strung beads, bead separating means, and means for winding a stitching thread around the bead thread between every two 75 stitches, the combination of projectable and retractable means, for supporting the bead thread laterally against the drag of the stitching thread, cooperating with the bead thread between the bead separator and the 80 fabric.

12. In a bead sewing machine embodying 85 means for supplying a thread carrying loosely strung beads, bead separating means, and means for winding a stitching thread around the bead thread between every two 90 stitches, the combination of vertically and laterally movable means, for supporting the thread laterally against the drag of the stitching thread, cooperating with the thread between the bead separator and the 95 fabric.

13. In a bead sewing machine embodying 95 means for supplying a thread carrying loosely strung beads, bead separating means, and means for winding a stitching thread around the bead thread between every two 100 stitches, the combination of movable mechanical means adapted to propel the beads forward beyond the separator and also to support a bead thread laterally against the 105 drag of a stitching thread and to interpose between the stitching thread and a bead and prevent the fouling of the stitching thread by its passing under a bead a second time.

14. In a bead sewing machine embodying 110 means for supplying a thread carrying loosely strung beads, bead separating means, and means for winding a stitching thread around the bead thread between every two 115 stitches, the combination of unitary movable mechanical means adapted to propel the beads forward beyond the separator and also to support a bead thread laterally against the drag of the stitching thread and to interpose between the stitching thread and a bead and prevent fouling of the stitching thread by its passing under a bead a second time.

15. In a bead sewing machine embodying 120 means for supplying a thread carrying loosely strung beads, bead separating means, and means for winding a stitching thread around the bead thread between every two 125 stitches, the combination of movable mechanical means adapted to propel the beads forward beyond the separator and also to intermittently support a bead thread laterally against the drag of the stitching thread and to prevent fouling of a stitching thread 130 by its passing under a bead a second time.

16. In a bead sewing machine embodying means for supplying a thread carrying loosely strung beads, bead separating means, and means for winding a stitching thread around the bead thread between every two stitches, the combination of vertically and laterally movable mechanical means adapt-

ed to propel the beads forward beyond the separator and also to support a bead thread laterally against the drag of the stitching thread and to prevent the fouling of a stitching thread by its passing under a bead a second time.

JOSEPH A. GROEBLI.
